UNITED STATES PATENT OFFICE.

THOMAS K. KNAPP, OF DANSVILLE, NEW YORK.

IMPROVEMENT IN MOP-HEADS.

Specification forming part of Letters Patent No. 151,404, dated May 26, 1874; application filed April 10, 1874.

To all whom it may concern:

Be it known that I, THOS. K. KNAPP, of Dansville, in the county of Livingston and in the State of New York, have invented certain new and useful Improvements in Mop-Heads; and do hereby declare that the following is a full, clear, and exact description thereof, reference being had to the accompanying drawings and to the letters of reference marked thereon, making a part of this specification.

The nature of my invention consists in the construction and arrangement of a mop head and handle, as will be hereinafter more fully set forth.

In order to enable others skilled in the art to which my invention appertains to make and use the same, I will now proceed to describe its construction and operation, referring to the annexed drawing, in which—

Figure 1 is a side view of my mop head and handle, showing the head open and drawn up on the handle. Fig. 2 is a longitudinal section, showing the mop in place. Fig. 3 is an enlarged side view of a sliding collar or sleeve on the handle.

A represents a wooden handle of any suitable dimensions, provided with an elongated ferrule, B, which is fastened to the handle by means of a single pin, a', which pin also secures the end of a central rod, C, projecting a suitable distance beyond the end of the handle, and also a spring, D. The spring D lies in a slot in the side of the ferrule B, and in a groove in the wooden handle A, and the end of the spring passes on the inside of the un-slotted portion at the end of the ferrule, and forms two catches, a and b, as shown in Fig. 2. The rod C has a cross-bar, C', firmly attached to its outer end. E represents a collar or sleeve sliding upon the ferrule B, and provided on opposite sides with notches x, one at each end, for the catches a b of the spring D to enter and hold the sleeve firmly in place. Both catches operate to prevent the sleeve from turning: the catch a prevents it from moving up on the handle, and the catch b prevents it from coming off of the handle. Longitudinally upon opposite sides of the sleeve E are recessed ribs or projections d, for the reception of the ends of two rods or arms, G G. The extreme upper ends of these rods are bent inward, entering corresponding holes in the

ribs d, and are fastened by pins y passing through the same. The arms or rods G G run parallel with the center rod C for a certain distance, then bend outward, as shown at e e, and the ends again run parallel with, but at a greater distance from, the center rod C. The ends of the arms or rods G G are cut with suitable screw-threads, and set-nuts f f are screwed up thereon. The ends beyond said nuts pass loosely through an elongated jaw, H', and attached to a similar jaw, H, both of said jaws having center holes, through which the rod C passes. The jaws H H' are constructed as shown in Fig. 2—that is, in the form of a half-hexagon-shaped tube—making them concave longitudinally on their under sides. The arms G G are of such length that when the sleeve E is held between the catches a b of the spring D, as above described, the cross-bar C' of the rod C will lie within the jaw H, as seen in Fig. 2. On the sides of the handle A are formed projecting ribs h h, as shown in Fig. 1. The mop is passed between the jaws H H' and fastened by screwing down the set-nuts f f, when the head is forced down in place, and held by the sleeve E being caught between the catches a b, and the mop is ready for use. The rods or arms G are made octagon or hexagon, or any other suitable shape, except round, and, running parallel with the center rod C, they form a convenient hand-hold for one hand in wringing out the mop. The flanges or ribs h on the handle form the hold for the other hand, so that the wringing of the mop can be easily accomplished.

Having thus fully described my invention, what I claim as new, and desire to secure by Letters Patent, is—

The combination of the angular arms G G, with screw-threads at their lower ends, the nuts f f, plates H H', and center rod C, with bar C', with the sleeve E and spring D on the handle A, all constructed substantially as and for the purposes set forth.

In testimony that I claim the foregoing I have hereunto set my hand this 8th day of April, 1874.

THOS. K. KNAPP.
